Mr. Brown, Compt.

United States Patent Office.

HORACE C. WILCOX, OF WEST MERIDEN, CONNECTICUT.

Design No. 2,654, dated May 14, 1867.

DESIGN FOR A SPOON OR FORK-HANDLE.

The Schedule referred to in these Letters Patent and making part of the same.

TO ALL WHOM IT MAY CONCERN:

Be it known that I, HORACE C. WILCOX, of West Meriden, in the county of New Haven, and State of Connecticut, have invented a new and useful Design for Spoon and Fork-Handles; and I do hereby declare that the following is a full, clear, and exact description of the same, reference being had to the accompanying drawings, making a portion of this specification, in which—

Figure 1 is a side view of a fork or spoon-handle, made according to my design.

Figure 2 is an edge view of the same.

Figure 3 is a transverse section of the same, taken in the line $x\ x$ of fig. 1.

Figure 4 is a transverse section of the same, taken in the line $y\ y$ of fig. 1.

Similar letters of reference indicate corresponding parts in all the figures.

The fork or spoon-handle, as the case may be, is curved in the manner shown more clearly in fig. 2. The shank A of the handle is formed with a double bead, a, at either edge, and with a flattened rib, b, at its central part. At the upper end of the shank aforesaid, between the same and the broad end portion B of the handle, is an enlargement, C, the lateral edges of which are shaped as shown in fig. 1, and are provided with a double bead, a', corresponding to that of the shank A. The upper ends of the beads a' are extended inward and upward in relief, upon the lower part of the portion B, and form a crossed or interlaced figure, as shown at c. The portion C is of elongated or oval form, as represented in the fig. 1, just mentioned, and is furnished at each of its edges with a double bead, e, the inner ends of the aforesaid double beads crossing the beads a' of the enlargement C, and being joined at their extremities within the same, as shown at a*. The outer ends of the beads e terminate in a leaved figure, f, formed in relief at the upper or outer end of the portion B. Formed upon the enlargement C, at the joined inner ends of the double beads e, is a figure in relief, consisting of flattened radial petals f', coiled tongues f'', and central angular elevation f*. The surface of the enlargement C, at each side of the figure just described, is formed with fine ridges or corrugations, situated longitudinally with reference thereto as indicated at g'.

What I claim as my invention, and desire to secure by Letters Patent, is—

The design and configuration of a fork or spoon-handle, substantially as herein set forth and shown.
